DESIGN FOR A CENTERPIECE FOR A TABLE OR SIMILAR ARTICLE

Marcel O. Lusinchi, San Anselmo, Calif.

Application January 13, 1942, Serial No. 105,175

Term of patent 3½ years

To all whom it may concern:

Be it known that I, Marcel O. Lusinchi, a citizen of the United States and a resident of the city of San Anselmo, county of Marin, State of California, have invented a new, original, and ornamental Design for a Center Piece for a Table or Similar Article, of which the following is a specification, reference being had to the accompanying drawings, forming part thereof.

I claim:

The ornamental design for a center piece for a table or similar article, as shown.

MARCEL O. LUSINCHI.
